(57) CLAIM

The ornamental design for a gas lighter head, as shown and described.

DESCRIPTION

FIG. 1 is a front elevational view of the gas lighter head of the invention;

FIG. 2. is a side elevational view;

FIG. 3 is a side elevational view of the opposite side;

FIG. 4 is a plan view;

FIG. 5 is a front perspective view; and,

FIG. 6 is a rear perspective view.

The dashed lines in FIGS. 1, 2, 3, 5, and 6 showing a lighter body are used for illustrative purposes only, the body forming no part of the claimed design.
